UNITED STATES PATENT OFFICE.

GEORGE O. HARRIS, OF VERMILION, SOUTH DAKOTA.

VALVE-LIFTER.

1,258,214.

Specification of Letters Patent.

Patented Mar. 5, 1918.

Application filed May 12, 1917. Serial No. 168,168.

To all whom it may concern:

Be it known that I, GEORGE O. HARRIS, a citizen of the United States, residing at Vermilion, in the county of Clay and State 5 of South Dakota, have invented certain new and useful Improvements in Valve-Lifters, of which the following is a specification, reference being had therein to the accompanying drawing.

10 This invention comprises a valve lifter. More specifically, it is directed to an apparatus for compressing and retaining under compression a spring which normally surrounds a valve stem while a retaining pin 15 may be inserted or removed from the stem.

In a practical application of a device of this kind, the space wherein it is to be used is generally limited. For this reason it is desirable to have a compact and simple instrumentality with few parts which when applied to an automobile, for example, may be used without the removal of the manifolds. It is likewise desirable to provide for quick adjustment of the parts and arranging them so that when thus adjusted this same adjustment may be utilized for a number of machines. It is likewise advisable to have a structure wherein the device may be, when not in use, placed flat upon the ground in which position it is not likely to be bent or distorted in a manner which might interfere with the normal working of its parts.

It is the primary object of the present invention to provide an instrumentality which will embody the features above enumerated and which in addition thereto will have but few parts readily assembled and capable of quick adjustment and being adapted for use 40 in practically all of the standard engines on the market at the present time.

Other objects and advantages will in part be apparent and in part be brought out in the description which follows.

45 A drawing illustrating an embodiment of the invention is hereto appended, in which the following views are shown:—

Figure 1 is a side elevation showing an application of an embodiment to a valve 50 of an internal combustion engine, a portion of the view being broken away for convenience of illustration.

Fig. 2 is a vertical sectional view on the lines 2—2 of Fig. 1 and looking toward the 55 right.

Fig. 3 is a detail view in perspective of a portion of the device.

Referring specifically to the drawings, the numeral 1 designates a body portion or back plate having at its upper end an angulated 60 extended portion 2 which is in turn provided at its outer extremity with a valve-head engaging member 3 threaded into the end of said arm and capable of being locked in different positions of adjustment for 65 which purpose a thumb piece 4 and clamping nut 5 may be used.

Upon the back plate or body portion 1 there are mounted straps 6 which are adapted to encircle and retain in sliding engagement with said back plate a slidable member 7. This member has at its lower portion an angulated arm 8 which at its outer extremity is formed into a fork member 9.

Upon the upper extremity of this member 7 there is pivotally mounted a lever 8' which lever is pivoted at its end to the end of the member 7.

Connecting this lever and one of the strap members 6 there is a link 9 the lower portion of which is secured to the strap suitably as by means of a bolt 10 the other end thereof being pivotally connected to lever 8' as by means of a connecting member 11.

For the purpose of effecting an adjustment between the lever 8' and one of the straps 6 there are provided a plurality of openings 12 on the lever intermediate its ends and the link 9 may also be provided with additional openings 13 whereby the 90 sweep of the lever may be changed by changing the location of the pivot point 11 in the various openings 12 in the lever or by moving the bolt 10 into one of the openings 13 on the link.

95 In its practical application, as illustrated in Fig. 1 the stem portion 3 is threaded down by means of the thumb nut onto a valve head 14 the lever 8' being preferably in raised position as shown. The spanner member 9 is made to encircle a washer or the like 15 which is usually provided on the lower end of a spring 16 which encircles the valve stem 17. When in this position, the lever 8' is then pressed down into the position shown in dotted lines whereupon the spring is compressed to the position indicated in dotted lines and the retaining pin 18 may then be removed.

100 The location of the pivot point 11 which 110

connects the link 9 with lever 8' is so arranged that when the lever is pressed down into the position shown in dotted lines in Fig. 1 the pivot point 11 will be out of alignment with the pivot point of the outer end of the lever and the lower end of the link, thus effecting a locking of the lever in its lowered position.

From the foregoing it will be apparent that the valve lifter which comprises the subject matter of this invention provides a quick adjustment for the valve head engaging member which may then be locked in its adjusted position, and then a positive lever actuation of the spring compressing member by means of a lever and link connection which makes a very practical arrangement and effects a quicker compression of the spring than was possible in devices wherein the threading of the member 3 was utilized to compress the spring.

It will also be apparent that the added adjustment provided by the openings arranged in the link 9 and lever 8 gives this device a large range of uses while its flat and compact form permits its being run over by a car, for instance, without impairing its utility or damaging its working parts.

While I have disclosed the invention in the embodiment herein illustrated, it will be understood that I do not desire to limit myself to the precise form of this disclosure, as such changes may be made in the construction and general arrangement as defined by the appended claims.

What I claim is:

1. A valve lifter comprising a body portion; an angulated arm disposed thereon; a valve-head engaging member adjustably mounted on said arm; a slidable member mounted for movement on said body portion; an angulated arm disposed on said slidable member; a valve stem spanner disposed on said angulated arm; a lever pivotally mounted at one end upon said slidable member; and a link secured to said body portion and to said lever.

2. A valve lifter comprising a body portion; an angulated arm disposed thereon; a valve-head engaging member adjustably mounted on said arm; a slidable member mounted for movement on said body portion; an angulated arm disposed on said slidable member; a valve stem spanner disposed on said angulated arm; a lever pivotally mounted at one end upon said slidable member; a link secured to said body portion and to said lever; and means for positively

locking said valve-head engaging member in a plurality of positions on said angulated arm.

3. A valve lifter comprising a body portion; an angulated arm disposed thereon; a valve-head engaging member adjustably mounted on said arm; a slidable member mounted for movement on said body portion; an angulated arm disposed on said slidable member; a valve stem spanner disposed on said angulated arm; a lever pivotally mounted at one end upon said slidable member; and a link secured to said body portion and to said lever, and provided with means for effecting an adjustment between said link member and said lever.

4. A valve lifter comprising a body portion; an angulated arm disposed thereon; a valve-head engaging member adjustably mounted on said arm; a slidable member mounted for movement on said body portion; an angulated arm disposed on said slidable member; a valve stem spanner disposed on said angulated arm; a lever pivotally mounted at one end upon said slidable member; and a link secured to said body portion and to said lever, said lever being provided with means for effecting an adjustment between said link and said body portion.

5. A valve lifter comprising a body portion; an angulated arm disposed on said body portion; a valve-head engaging member mounted adjustably on said angulated arm; means for locking said valve-head engaging member in a plurality of positions on said arm; a member slidably mounted upon said body portion; an angulated arm disposed on said slidable member and having at its outer end a valve stem spanning portion; a lever pivotally mounted at one extremity upon said slidable member; said lever having intermediate its ends a plurality of openings therein; and a link pivotally secured at one end in one of said openings and capable of adjustment with relation to said lever by moving said pivot point in the openings in said lever; said link being pivotally secured at its opposite end to said body portion, and being provided intermediate its ends with a plurality of openings for effecting an adjustment between said link and said body portion.

In testimony whereof I affix my signature in presence of two witnesses.

GEORGE O. HARRIS.
